UNITED STATES PATENT OFFICE.

CARL RICHARD JERNBERG, OF CHICAGO, ILLINOIS, ASSIGNOR TO STANDARD FORGINGS COMPANY, OF CHICAGO, ILLINOIS, A CORPORATION OF ILLINOIS.

APPARATUS FOR MAKING DROP-FORGED STEEL CAR WHEELS.

1,408,702.

Specification of Letters Patent.

Patented Mar. 7, 1922.

Original application filed September 4, 1919, Serial No. 321,597. Divided and this application filed November 15, 1920. Serial No. 424,281.

To all whom it may concern:

Be it known that I, CARL RICHARD JERNBERG, a citizen of the United States, residing at Chicago, in the county of Cook and State of Illinois, have invented certain new and useful Improvements in Apparatus for Making Drop-Forged Steel Car Wheels, of which the following is a specification, reference being had to the accompanying drawings, and to the reference characters marked thereon, which form a part of this specification.

This invention relates to apparatus for making forged steel car wheels, and more particularly relates to the roughing out and finishing dies used in the forging operations.

This application is a division of my former application, Serial No. 321,597, filed September 4, 1919. The advantages of the apparatus, and mode of operation thereof will be fully understood as I proceed with my specification.

In the drawings:

Fig. 1 illustrates in a perspective view, an ingot or blank from which the steel car wheel is to be forged by my improved apparatus.

Fig. 2 is a central, vertical, sectional view of a steel car wheel produced by the use of my invention.

Fig. 3 is a plan or face view of the upper die used in the first or roughing out operation.

Fig. 4 is a plan or face view of the upper die used in the second or finishing operation.

Fig. 5 is a plan or top view of the lower die used in the first or roughing out operation.

Fig. 6 is a side elevation, partly in section, of the upper and lower dies of Figs. 3 and 5, in juxtaposition, without the blank.

Fig. 7 is a plan or face view of the lower die used in the second operation.

Fig. 8 is a vertical elevation, partly in section, of the upper and lower dies of Figs. 4 and 7, in juxtaposition.

In said drawings, A will represent the blank or billet as a whole, substantially rectangular in shape and of dimensions less than the diameter of the proposed wheel, and having a thickness slightly in excess of

the width of the rim of the proposed wheel. Where, for example, I desire to make a car wheel the diameter of which at the tread is 33 $\frac{1}{4}$ inches, the thickness of the rim about 5 $\frac{1}{2}$ inches, having a flange projecting from the tread of 1 $\frac{1}{8}$ inch, and having a hub substantially 10 inches in diameter and 7 inches deep, I find that I can use a blank or billet of steel 6 $\frac{1}{2}$ inches thick by 22 inches square, weighing approximately 882 pounds. When such a blank is subjected to the drop forging operation by the apparatus herein illustrated and claimed, a wheel of the desired dimensions will be produced.

These figures are given by way of illustration and not as limitations; inasmuch as it will be manifest that blanks or billets of other dimensions may be used.

The letter B indicates as a whole a drop forged car wheel made from the billet or blank A by the use of my apparatus. Referring now more particularly to Figs. 3, 5 and 6, C will represent the upper die as a whole, D the lower die as a whole, E a suitable support or part of a drop forge adapted to sustain the lower die D. The support E is preferably provided on its top surface, upon which the die D rests, with a circular recess 1, in which is located one or more circular springs 2, 2. In the upper portion of the recess 1 and resting upon the top of the spring or springs 2, 2, is a circular boss 3 integral with the die D. The length of the springs is such as to cause the boss 3 to stand somewhat out of the recess 1, normally, thus slightly raising the lower surface of the die D above the support E, and affording the familiar cushioning action desirable in drop forge operations. The upper part of the recess 1 acts also as a bearing for the stud 3 so that the lower die D may be rotated about the longitudinal vertical axis of the stud 3. This rotation may be accomplished by any suitable means, but I have illustrated as one means a plurality of projections or sprocket teeth 4 located at equal distances apart around the periphery of the main or body portion of the lower die D. These sprocket teeth are adapted to be engaged by a sprocket chain actuated from any suitable source of power (said sprocket chain and means for actuating it not being shown),

whereby said lower die D may be given a suitable rotary motion over the plane of the upper surface of the support E.

The upper die C is provided with a suitable upstanding flange member 5, adapted for attachment to the reciprocating hammer head (not shown) of any suitable hammer. The proximate faces of the upper and lower dies C, D, are complementally recessed in the manner and for the purposes herein-after described. It will be noted, however, that the lower die 5 is circular and of a size in excess of the ultimate diameter of the car wheel, while the upper die C is relatively long and narrow, with arcuate recesses and projections.

Referring now more particularly to the lower die (Figs. 5 and 6) it will be seen that a circumferential recess 6 is cut in its face 13 to a depth substantially equal to the thickness of the rim b of the wheel B. Said recess 6 has a slightly tapered outer wall 7 terminating in a somewhat rounded fillet 8. The diameter of the recess 6 is substantially the same as that of the circumferential diameter of the tread of the finished wheel. The inclined inner wall 9 of this recess extends upwardly and inwardly from the bottom 10 and terminates in a horizontal surface 12 lying in a plane somewhat below the top surface 13 of the die D. An annular recess 14 is cut in the face of the surface 12, so that its bottom 15 is in substantially the same horizontal plane as the bottom 10 of the recess 6. The two side walls of the recess 14 flare outwardly somewhat from the bottom 15 toward the surface 12. This annular recess 14 forms a centrally projecting tapered boss 16, the top edge of which may be very slightly rounded.

The upper die C is of a length slightly in excess of the diameter of the recess 6, as clearly illustrated in Fig. 6. Its width is considerably less than the diameter of said recess 6, as clearly shown in Fig. 3. Longitudinally of the face 17 of said die is a rib 18, narrower than the width of the face 17. This rib 18 is provided with a centrally located, outwardly projecting tapered boss 19; the taper and the diameter of this boss corresponding with the taper and diameter of the boss 16 of the lower die, as clearly shown in Fig. 6. Surrounding the boss 19 are arcuate or segmental recesses 20, one on each side of the boss 19, said arcuate recesses extending transversely of the rib 18. Between the recesses 20 and the extreme end of the rib 18, said rib is curved or rounded as indicated by the surfaces 21; said rounded surface 21 merging into the flat or horizontal surfaces 22, 22, one at each end of the rib 18.

It will be seen by reference to Fig. 3 that the transverse dimension of the contacting surfaces of the upper die C are substantially the same or only slightly greater in width

than the diameter of the central boss 19. This construction proximates a narrow head or peaning hammer in the drop forging action. In use, the dies C and D have the blank A placed between them, the blank resting on the lower die D, and as the latter revolves upon its central vertical axis, the upper die C is given a reciprocating action by the drop forge or hammer and repeatedly strikes the blank A, but at a different place each time, since the blank A rotates with the lower die D. This produces the necessary roughing out of the blank A and reduces it to a shape or form which in cross-sectional area would approximate the space between the dies C and D illustrated in Fig. 6. That is to say, the blank A would be caused to approximate the shape of the wheel B by having a central hub and an outer flange roughed out, connected by a central or horizontally disposed disc or web; the hub having a central recess punched therein from both sides,—the two not, however, communicating with each other.

Referring now to Figs. 4, 7 and 8, F is a lower die as a whole, G is the upper die as a whole; the lower die resting upon the support E. The lower die F is also provided with sprocket teeth 4. The die F differs from the die D only in the contour or shape of its upper face. It will be seen that it is provided with two concentric recesses 23, 24. The inner recess 24 has tapered walls, the outer one terminating in a curve as indicated at 25. This centrally located recess 24 does not extend as deeply into the die as does the recess 23, as clearly indicated in Fig. 8, and forms in the finished product one side c of the hub d of the wheel B. The outer wall of the recess 23 forms the tread of the wheel and said wall terminates at its upper end where it joins the surface 26 of the die F, in a suitably curved or recessed part 27, which part in connection with a complementary part on the upper die G will form in the finished wheel the flange e. The inner wall 28 of the recess 23 is given a suitable curve 29 until it meets the curve 25 of the recess 24. This portion 29, together with the complementary part of the upper die G, forms one side f of the web of the car wheel B, connecting its hub d with the rim e.

The curved or recessed part 27 is of the shape and one-half of the thickness of the flange e of the finished wheel B. 30 is the central hub or boss projecting upwardly from the bottom of the inner annular recess 24.

Referring now more particularly to Figs. 4 and 8, the upper die G comprises a rectangular rib or plate 31 of a length substantially equal to the diameter of the lower die F, but of a width materially less. It is provided on its back with a longitudinally

extending and upwardly directed head 32 by which it may be secured in any suitable or convenient manner to the reciprocating head or part of the drop forge. On its face, the 5 upper die G is provided with a projecting tapered hub or boss 33, corresponding with and substantially of the same dimension and configuration as the hub or boss 30 of the lower die F. On either side of this hub 33 10 are segmental ribs g each of which is provided with suitable recesses and projections corresponding with and complementary to the lower die. For example, the recess 34 corresponds with the recess 24 of the lower 15 die and the recess 35 corresponds with the recess 23 of the lower die. The rounded parts 36 and 37 correspond with the rounded portions 25 and 28 of the lower die, while the undulating surface 38 of the upper die G 20 is complementary to the undulating surface 29 of the lower die. It will be observed that the recesses and projections just described, on the segments g, extend in a direction transversely of the upper die G or more 25 properly stated, are formed upon the arc of a circle drawn about the center of the boss 33.

When the blank is submitted to the forging action of the dies, F and G, the lower die 30 being constantly rotated and the upper die G being given the familiar drop forging reciprocating action, said blank will presently assume a shape corresponding to the finished product, as shown in Fig. 2. It will be 35 noted that the upper die G will not impinge upon the blank at the same spot twice in succession, owing to the rotation of the lower die F during the forging operation. When the finishing operation on the blank by 40 means of the dies F and G has been completed, the blank will be in the shape and configuration shown in Fig. 2, with these exceptions: first, there may project from the flange e a very slight burr or fin, and there 45 will be found in the hub e a central transverse web indicated by the dotted line at h. The rest of the wheel will be in finished shape. The finishing off will consist in removing the burr or fin, if any, from the 50 flange e, and in punching out the web h and boring the hub to a proper diameter to fit upon a car axle. So far as the forging operation is concerned, the diameter of the wheel, the thickness of the tread, the size and shape 55 of the hub and the curved web connecting the hub and the tread and the size and shape of the flange on the tread, are all completed and finished by the use of the dies F, G, and require no further machining.

60 It will be noted that a concentric groove 40 is provided in the face of the lower die F, to take care of any surplus metal in the fin or burr that may extend from the flange of the completed wheel.

65 I am aware that it has been heretofore a

practice to make a cast steel car wheel by placing a blank in a suitable press between opposing dies, having suitable complementary faces, and subjecting the blank to heavy pressure; but in such operation, the face of 70 the upper die has necessarily been formed complementary to the proximate face of the lower die and of the same diameter. I believe it to be new to use for the upper member of the pair of dies, a die which is 75 substantially narrow in cross-section.

I have found by repeated experiments that the narrow die (upper) shown in Fig. 3, produces the best results; that the metal more readily conforms to the proper shape 80 and is molded and welded and stretched and pushed into proper position without lacerating, so to speak, the grain or fibre of the metal; and that the finished product produced from the dies herein illustrated and 85 described is more perfect and durable in use.

I find also that the cost of the upper dies, Figs. 3 and 4, is considerably less than the cost of the dies required in hydraulic pressing operations, and that the time required to 90 manufacture the car wheel such as shown in Fig. 2 by the use of my improved dies is considerably less than that required in the pressing operations.

It follows, therefore, that by the use of my 95 dies the cost of manufacture of steel car wheels is greatly reduced.

While I have shown and described in detail, certain specific shapes and forms of recesses and grooves in the die surfaces, it 100 will be understood that modifications of these shapes and forms may be made to correspond with the contour of the car wheel to be fabricated. I therefore desire my invention not to be limited to the specific form 105 herein illustrated, except as hereinafter set forth in the appended claims.

I claim as my invention:

1. An apparatus for roughing out the blank in the forging of steel car wheels, comprising a pair of roughing out dies, the lower die having an annular recess in its upper face, the outer side wall of which is substantially the diameter of the tread of the wheel, a central, circular boss raised up from the 110 bottom of said recess and of a height less than the depth of the recess, and an annular web forming projection intermediate said boss and the recess side wall, the upper die having an operating surface of a length 115 slightly greater and a width appreciably narrower than the diameter of the annular recess in the lower die, and provided with complementary projections and recesses to cooperate with the lower die, means for operatively attaching said lower die to a rotatable element and means for operatively attaching the upper die to a reciprocating element. 120

2. An apparatus for finishing the roughed out blank in the forging of steel car wheels, 130

comprising a pair of finishing dies, the lower die having an annular recess in its upper face, the outside wall of which is substantially equal to the diameter of the tread of the wheel, a circumferential groove in the face of the lower die terminating at its inner end with the top of the said side wall, the bottom wall of said recess being parallel with the face of the die, a central, circular 10 boss, the top of which is parallel with but below the face of the die, an annular circumferential recess surrounding said boss, the bottom of said recess being parallel with the face of the die, said inner recess being of 15 less depth than the first mentioned or outer recess, and a web forming annular rib intermediate the said two recesses; the upper die

being of a length slightly greater than and of a width appreciably less than the diameter of the groove in the face of the lower die, and having complemental projections and recesses, means for operatively attaching the lower die to a rotating element and means for operatively attaching the upper die to a reciprocating element. 20 25

In testimony that I claim the foregoing as my invention I affix my signature in the presence of two witnesses, this 12th day of November, 1920.

CARL RICHARD JERNBERG.

Witnesses:
